UNITED STATES PATENT OFFICE.

NATHAN HATCH, OF ALBANY, NEW YORK.

UNION SUIT.

1,110,055.

Specification of Letters Patent.

Patented Sept. 8, 1914.

Application filed April 16, 1914. Serial No. 832,181.

To all whom it may concern:

Be it known that I, NATHAN HATCH, a citizen of the United States, and a resident of Albany, county of Albany, and State of New York, have invented certain new and useful Improvements in Union Suits; and I do declare the following to be a full, clear, and exact description of the invention, such as will enable others skilled in the art to which it appertains to make and use the same, references being had to the accompanying drawings, and to the letters and figures of reference marked thereon, which form a part of this specification.

This invention is a modification of that described and claimed in my application Serial Number 810,323 filed January 5th, 1914.

The invention relates to an article of wearing apparel, more particularly to union undergarments for men, women and children.

One of the objects of the invention is to construct a union suit to fit the body of the wearer perfectly and securely and to make it very easy to put on and take off the person of the wearer.

Another object is to construct a garment in which it is not necessary to provide the objectionable lines of buttons and button-holes or securing means which are usual in men's garments, which extend from the neck thereof to the crotch, thereby preventing the objectionable gaping due to the button structure.

Another object is to provide a union suit which is practically integral in the body portion thereof, no fastening such as buttons, buttonholes and the like being utilized in the central portion of the front of the garment, or in the vertical line up and down the back.

Another object is to provide a union undergarment in which the fastening means are of minimum number and arranged at the back and at the right and left sides just to the front of the hip joints of the wearer of the garment and substantially at the waist line thereof.

Another object is to provide a garment in which the opening for the insertion of the body of the wearer is situated substantially above the waist line thereof, and thereby produce a garment which is substantially integral in construction in the front portion, the back portion up to the

waist line thereof, and also around the chest and upper portion of the back portion.

Other objects will appear from the following description and claims.

The garment is especially useful for persons engaged in athletics, such as horseback riding and the like. The construction is such that the upper portion is practically continuous around the body, similar to ordinary sweaters or athletic undershirts, and the lower or leg portions of the garment are also continuous and are integral with the front part of the shirt portion and amply secured at the rear and side by the use of only a few, usually three, buttons or fastening means. It is also useful as a nightrobe.

The garment is so constructed that in putting it on the body, the legs of the wearer may be inserted into the leg portions in a manner similar to the ordinary way in which trousers are put on, and then the upper portion is placed upon the body of the wearer over the head in a manner similar to the way in which a sweater or athletic shirt is put on the body of the wearer. The rear portions of the garment are then closed and fastened by the securing means provided therefor, usually one at the small of the back, and the others, one at each side substantially at the waist line and just a little to the front, so that they may be conveniently manipulated.

Referring to the drawing forming a part of this specification: Figure 1 is a view of the front of a garment embodying my invention. Fig. 2 is a view of the rear of the garment embodying my invention with the parts secured together. Fig. 3 is a view of the rear of the garment embodying my invention, the back flap being raised. Fig. 4 illustrates the patterns of inserts for the seat portion.

In the detailed description of the invention, similar reference characters indicate corresponding parts.

The garment may be of either woven or knitted fabric, and except for the features of construction which embody my invention, the garment is made in the usual way, namely, the leg portions may be long or short, the arm portions long or short, the arm and leg ends are ribbed as usual, the neck being finished in the usual way.

The garment may also be provided with overlapping yet open construction to form

the fly and the usual open and overlapping substantially longitudinal opening in the seat portion thereof.

Referring to the drawings; A represents the integral body portion of the garment, B the leg portions, C the back flap, D is a belt strip or band having extended flaps or projections *d* and *d'*.

The body portion of the garment in front 10 and in the rear is made substantially of one continuous piece, the same being secured at the inside of each leg as indicated at *a*, *a'*, *a*. In the rear of the garment is provided a 15 horizontal slit substantially at the waist line thereof extending from points *b* and *b'* just above and to the rear of the hip joints. From these points substantially vertical slits are provided at each side of the garment to 20 points *c* and *c'* situated just below the arm pits. The edges of the slits are overlapped, that is the sides of the back flap overlap the small inner side flaps as at *e* and *e'*, so as not to expose the body of the wearer when 25 the back flap is in its closed position. The edges of the respective flaps are finished in the usual way.

At the rear of the garment substantially at the waist line thereof, and along the lower edge of the back flap, is secured a belt 30 or band portion D which may be made of the same material as the garment or other suitable material. Substantially at the center of the belt or band portion is a series of buttonholes *f* or other fastening means and 35 also on each of the flaps *d* and *d'* are provided a series of buttonholes or other fastening means *f* and *f''*. Buttons or suitable fastening means are provided on the garment at *g* and *g'*. The fastening means indicated at the center or small of the back is not absolutely necessary. Adjacent the buttons *g* and *g'* nearer the side of the garment, I have provided small bands or loops 40 *o* through which the flaps *d* and *d'* may be inserted. These bands or loops are not necessary, but may be used if desired.

By reason of the series of fasteners provided in the belt portion or waist band, the 45 position of the garment may be adjusted to suit the necessities of the wearer.

While I have shown buttons on one portion of the garment and buttonholes on the other, it is evident that the position of the two may be reversed, and that other suitable fastening means may be employed for the buttons and buttonholes.

The inserts *m*, *m'*, *m''*, and *n*, *n'*, *n''* shown in Fig. 4 form a part of the seat structure as shown in Figs. 2 and 3. Fastening means *s* are placed upon the outer 55 edge of one of the inserts, which is arranged

to co-act with another fastening means *t* upon the hip portion of the garment in a suitable place so that the rear flaps of the seat portion formed by these inserts may be held closed when desired.

As above stated the garment is applied to the person by the wearer stepping through the opening in the back and then lifting the upper or body portion, so that it may be 70 placed over the head, and the arms inserted into the armholes at the same time.

The belt or band on the lower portion of the back flap is then secured to the upper portion of the seat part of the back by the 75 fastening means shown and the tabs or flaps *d* and *d'* are inserted through the loops *o* at the sides and front and secured at *g'*, *f'* and *g''* and *f''* as shown.

By the construction disclosed, a garment 80 is provided which is substantially integral in the rear, the back opening being above the waist line, there being no seat flap, the seat portion being integral with the hip and front body portions.

I have illustrated and described the embodiment of my invention which I believe to be the one best subserving the object which I have in view, nevertheless the invention is not restricted in details except as these are 90 definitely expressed in the claims.

Having now described my invention, what I claim as new and desire to secure by Letters Patent is—

1. In a combination-garment comprising 95 a substantially integral front body portion, leg portions seat and hip portions and upper back portions, the central back portion consisting of a flap which overlaps at its lower edge, the upper part of the seat portion, a belt or band portion along the lower edge of the back flap and means for detachably securing the lower part of the back flap to the back and sides of the garment substantially at the waist line thereof. 100

2. In a union suit, a fixed seat portion and a back flap extending substantially over the lower portion of the back, a belt or band portion secured to the lower edge of the back flap, having tabs or flaps at each end, means 110 for adjustably and detachably securing the lower portion of the back flap to the upper part and outside of the fixed seat portion and the tabs or flaps to the front and sides of the garment.

In witness whereof I have hereunto set my hand at New York N. Y. this 31st day of March, 1914.

NATHAN HATCH.

In presence of—

JOHN J. RANAGAN,
AGNES C. O'CONNELL.
